UNITED STATES PATENT OFFICE.

HERBERT H. HILLMAN, OF GRAND HAVEN, MICHIGAN, ASSIGNOR TO CHALLENGE REFRIGERATOR COMPANY, OF GRAND HAVEN, MICHIGAN, A CORPORATION OF MICHIGAN.

REFRIGERATOR.

Application filed April 23, 1921. Serial No. 463,841.

To all whom it may concern:

Be it known that I, HERBERT H. HILLMAN, a citizen of the United States, residing at Grand Haven, in the county of Ottawa and 5 State of Michigan, have invented new and useful Improvements in Refrigerators, of which the following is a specification.

The present invention relates to refrigerators and the like; and its object is to provide 10 an improved lining for such a structure and improved means for securing such lining in place.

This object is attained by, and the invention finds preferable embodiment in, the 15 structure hereinafter particularly described and illustrated by the accompanying drawings, in which:

Figure 1 is a sectional view of the lower part of my refrigerator lining and of the 20 lower part of the body of the refrigerator, taken on a vertical plane corresponding to line 1—1 of Figure 2;

Figure 2 is a like view of the same taken on a horizontal plane corresponding to line 25 2—2 of Figure 1;

Figure 3 is a view in perspective of my lining for refrigerators and the like;

Figure 4 is a sectional view of the same taken on a vertical plane corresponding to line 30 4—4 of Figure 3; and

Figure 5 is a sectional view of said lining taken on a horizontal plane corresponding to line 5—5 of Figure 4, and thus exhibiting in top plan view the bottom member or portion of said lining.

In the embodiment of the invention chosen for illustration by the drawings and for detailed description in the body of this specification, a refrigerator is shown having a 40 body portion or frame designated generally 1 comprising the front side 2, right-hand side 3 and corresponding left-hand side (not shown). This front side 2 has a door opening closed by a door 4 hinged at 5. My lining for the refrigerator, preferably of metal "porcelained," has an open-front registering with the door opening of the body of the refrigerator as shown, side portions 6, 7 adjacent its open front, a back portion 8, top portion 9, and a bottom portion or member 10, which in the construction shown is formed of different piece from that compos-

ing the side, back and top portions, being joined thereto at the lower edge 10¹ of the side and back portion. The bottom portion or member 10 is hollow as shown, having a raised peripheral rim 11 a part 12 whereof, which is adjacent the open front of the lining, extends first outwardly at 13 and then downwardly at 14, thus forming a depending 55 flange—said downwardly extending part 14. The sides 6, 7 have respectively outwardly turned flanges 15, 16, and the top portion 9 has a similar outwardly turned flange 17. These flanges 15, 16, 17 are held between 60 the inner side of members 18 of the body and the retaining members or strips 19, as by screws 20, and the downwardly extending portion or flange 14 of the bottom's rim is similarly held between the inner side of 65 the member 21 of the body and a retaining member or strip 22 as by screws 23. It will be seen that the rim's part 13 extending forwardly toward the door further than the flanges 15, 16 of the sides 6, 7 extend, the 70 retaining member 22 is located nearer the front of the refrigerator than are the retaining members 19 which hold the sides' flanges 15, 16 in place.

A drain orifice 24 is provided in the 75 bottom member 10 as shown. It will be seen that water, etc. cannot run out of the refrigerator door, but may readily flow through the orifice 24, thus keeping the front of the refrigerator dry and clean; and also that 80 the lining is securely held in the refrigerator's body in the manner described.

Finishing strips 25, 26 may be attached as shown.

The invention being intended to be 85 pointed out in the claim, is not to be limited to or by details of construction of the particular embodiment thereof illustrated by the drawings or hereinbefore described.

I claim:

In a refrigerator and the like; a body 90 having a door in its front side; an open-front lining for the body having sides adjacent its open front provided with outwardly turned flanges, and having a bottom provided with a raised rim comprising a first portion extending upwardly and substantially 95 in the vertical plane in which lie the extremities of said flanges, a second portion 100

extending beyond said flanges outwardly toward the door and a third portion extending downwardly from said second portion; retaining members fastened to the inside of the body and holding said flanges between them and the body; and a retaining member in substantially the same vertical planes as

the first-mentioned retaining members and engaging between said first and third portions and secured to the body.

In testimony whereof I have hereunto set my hand at Grand Rapids, Michigan, this 19th day of April, 1921.

HERBERT H. HILLMAN.
